UNITED STATES PATENT OFFICE

CLAUDE H. DANIELS, OF NEWTON CENTER, MASSACHUSETTS

DESIGN FOR A SHOE

Application filed January 28, 1920. Serial No. 34,326. Term of patent 14 years.

To all whom it may concern:

Be it known that I, CLAUDE H. DANIELS, a citizen of the United States, and a resident of Newton Center, in the county of Norfolk and State of Massachusetts, have invented a new, original, and ornamental Design for a Shoe, of which the following is a specification, reference being had to the accompanying drawing, forming part thereof.

Referring to the drawing:

The figure is a front perspective view of a shoe showing my new design.

The invention of the present application resides in ornamenting the vamp of a shoe, by perforating substantially the entire vamp

with a mass of substantially equi-spaced, substantially equi-sized apertures which extend completely through the upper materials constituting the vamp, the exposed material of the vamp remaining between each pair of apertures being approximately the same width as said apertures, the design being shown as applied to a shoe of conventional shape.

I claim:

The ornamental design for a shoe, substantially as shown and described.

In witness whereof, I hereunto subscribe my name this twentieth day of January, A. D., 1930.

CLAUDE H. DANIELS.
